ORGAN VALVE

Filed March 17, 1931

UNITED STATES PATENT OFFICE

HENRY E. BURTON, OF HAGERSTOWN, MARYLAND, ASSIGNOR TO M. P. MOLLER, INC., OF HAGERSTOWN, MARYLAND, A CORPORATION OF MARYLAND

ORGAN VALVE

Application filed March 17, 1931. Serial No. 523,371.

This invention relates to electro-magnetic valves and more particularly to magnet valve units arranged to control the supply of air to the action box or other pneumatics associated with a pipe organ or similar device.

Magnet valves of this type are usually formed as an integral unit adapted to be attached to the outside of the action box with which they are associated. The valve elements in these units are extremely delicate in action and frequently become clogged by particles of sawdust or other foreign matter carried into the action box by the air flowing therein. In many organ installations, these valves are placed in dark and inaccessible places about the organ structure, and when it becomes necessary to repair or adjust them for any reason, considerable difficulty has been experienced in properly replacing and adjusting the valve parts. It frequently happens that during assemblage or adjustment of these valves, the little disc armature valve element becomes disarranged relative to its valve seat and sometimes actually blows away before the parts are assembled and thus causes considerable annoyance and waste of time to the mechanic in making these repairs.

The object of the present invention is to provide an improved electro-magnetic organ valve construction which shall facilitate the assemblage and operation of the valve parts and this object is accomplished by mounting all of the movable or adjustable valve parts on a removable closure element for the valve casing so that these parts may be removed from the valve casing as a unit without disturbing the adjustment or operative relation of the valve parts.

Another object of the invention is to provide a valve unit of the character designated having a guide member for the movable valve element which shall also positively retain the same in the normal operative relation to its valve seat whenever the unit is removed from the casing for any reason.

A further object of the invention is to provide a magnet valve unit of the character designated which shall be durable in con-

struction and more efficient in operation than similar valves heretofore employed.

These and other objects of the invention will be more manifest from the following description and drawing, and specifically set forth in the appended claims.

In the drawing:

Figure 1 is a sectional view of an organ wind box employing a magnet valve embodying my invention.

Figure 2 is a view in section of the valve element.

Figure 3 is a perspective view, showing the relation of the removable valve parts, and

Figure 4 is a top view of the valve casing.

Referring to Fig. 1 of the drawing, the numeral 10 indicates a wind or action box of a pipe organ employing a magnet valve constructed in accordance with my invention. This valve unit comprises a hollow metallic casing 11 and an electromagnet 12 having its pole pieces 13 mounted in the wall thereof which is attached to the organ action box in a manner well understood in the art.

The interior of the casing 11 is arranged to form a valve chamber 14 and this chamber communicates with an outlet 15' by means of a conduit 16 also formed in the valve casing. The lower side of the casing is open and is provided with a removable cover plate or member 15. The arrangement of the casing is such that the air chamber and associated conduit may be made at a single die casting operation and thereby provide a valve casing which is simple in construction and more durable than similar devices now on the market.

The cover member 15 carries an adjustable tube member 17 which forms a communication to the interior of the valve chamber and the inner extremity of this tube forms a valve seat 18 for an armature disc valve element 19 which is controlled by the pole pieces of the electro-magnet. Associated with the inner extremity of the cover 15 is a valve guide member 20. This member is in the form of a cage arranged to guide the lateral movement of the valve and retain the same relative to its valve seat whenever the cover is removed. The upper end of the guide is provided with

a flanged opening 20' so that the operation of the valve element will not be impaired and at the same time prevent the valve element from being permanently removed from the valve seat should the cover be accidentally dropped by the workman when he is assembling or otherwise adjusting the valve parts. While I have shown this valve retaining means as a flange, it is obvious that various other means may be employed at the top of the guide, such as overhanging clip or finger projections. To facilitate the passage of air through the valve chamber the valve guide is perforated with openings 21 and some of these openings connect with slits 22-22 to form resilient clips at the bottom of the guide to hold the same in place on the cover 15. In the illustrated embodiment of my invention, the cover plate 15 is provided with a threaded portion 23 and a shoulder 24 which serves as a mounting for the valve guide. The relation of these parts is shown in Fig. 3.

The valve disc 19 for controlling the flow of air through the valve casing is provided with a double sealing surface. A metallic surface 25 lies adjacent the magnet pole pieces and on the opposite side is a paper or fibre surface 26 which engages the valve seat 18. The lower portion of the disc is provided with a flange 27 which grips the fibre disc and also forms a limit stop which engages the edges of the flanged opening 20' and prevents the disc from being accidentally lost or removed from the valve unit. This valve element is shown in Fig. 2.

The top portion of the valve casing is provided with an opening 28 which is located between the pole pieces of the magnet and forms a communication between the valve chamber 14 and an opening 29 in the wind box to which the valve may be attached. The relation of the air openings to the valve chamber is shown in Fig. 4.

Having thus described a valve unit embodying my invention, one of the important features is the provision of a one-piece valve casing provided with a cover member which shall contain all of the movable valve parts so that the same may be removed from and reinserted into the valve casing without removing the valve casing from its fixed support or otherwise changing the particular valve parts. By thus providing a removable unit including the casing cover, valve guide and retaining means for the disc valve element which shall positively retain the element in operative relation to its valve seat, these parts may be quickly and readily adjusted prior to inserting them in the operative position in the valve casing.

The opening at the top of the guide is adapted to receive the top portion 25 of the valve disc so that it shall engage the top wall and close the opening 28 when the disc is actuated by the electro-magnet. When the

valve parts are in operative relation, as shown in Fig. 1, the guide 20 surrounds the disc valve so that when the cover is removed for any reason, the flange 20' positively prevents the valve element from being accidentally displaced or lost. The valve element may be removed from its seat or otherwise disassembled by unclamping the guide from the cover. In the illustrated embodiment of my invention this guide is frictionally clamped to the cover, but it is obvious that it may be fixed to the cover by screw threads or equivalent securing means, if so desired.

While I have shown and described a preferred embodiment of my invention, it is obvious that various changes may be made therein without departing from the scope of the invention as set forth in the claims.

What I claim is:

1. In an electro-magnetic organ valve, the combination with a valve casing having an opening in one side thereof, of a closure member for the opening including a tubular member arranged to form a valve seat, a disc valve element freely movable relative to the seat, and a valve guide having means for limiting the vertical movement of said valve disc and for positively retaining said valve element in operative seating relation to said valve seat.

2. In an electro-magnetic organ valve, the combination with a valve casing having an opening in one side thereof, of a closure member for the opening including a tubular member arranged to form a valve seat, a disc valve element freely movable relative to the seat, and a guide surrounding the valve seat and carried by the closure, said guide including peripheral means at the top portion thereof for positively retaining said valve element in operative seating relation to the valve seat.

3. In an electro-magnetic organ valve, the combination with a valve casing having an opening in one side thereof, of a closure member for the opening including a tubular member arranged to form a valve seat, a disc valve element freely movable to the seat, a removable valve guide supported by said closure, and means for attaching the guide to the closure member.

4. In an electro-magnetic organ valve, the combination with a valve casing having an air chamber formed therein, of a removable cover for one side of the chamber, a valve seat forming an integral part of said cover, a disc valve element located in said chamber and freely movable relative to said seat, and a valve guide having a top portion of smaller size than said disc whereby the disc is positively retained in operative seating relation to said seat.

5. In an electro-magnetic organ valve, the combination with a valve casing having an opening in one side thereof, of a removable cover for the opening including a valve seat,

- an electro-magnet mounted in the opposite wall of said casing, a disc valve element having a raised central portion, a valve guide mounted on said cover and having inwardly projecting portions at the top thereof arranged to form an opening to receive the central portion of the disc when actuated by said magnet.
6. In an electro-magnetic organ valve, the combination with a valve casing having an opening formed in one side thereof, of an electro-magnet mounted in another side and opposite said opening, a closure member for the opening, a disc valve member located in said casing and arranged to be operated by said magnet, a valve guide carried by the closure, yieldable means for attaching said guide to said closure, and means for securing the closure member to the casing by rotational movement of said closure member.
7. In an electro-magnetic organ valve, the combination with a valve casing having an opening formed in one side thereof, of an electro-magnet mounted in another side and opposite said opening, a closure member for the opening, a disc valve member located in said casing and arranged to be operated by said magnet, a valve guide carried by the closure, and means at the upper portion of said guide for retaining said valve element in operative seating relation to said valve seat.
8. In an electro-magnetic organ valve, the combination with a valve casing having an opening formed in one side thereof, of an electro-magnet mounted in another side and opposite said opening, a rotatable closure member for the opening, a disc valve member located in said casing and arranged to be operated by said magnet, and a valve guide carried by the closure for limiting the lateral and vertical movement of said valve member.
9. In an electro-magnetic organ valve, the combination with a valve casing having a threaded opening in one side thereof, of a threaded closure member for the opening, a valve seat forming an integral part of said closure member, a disc valve member, and a detachable guide mounted on said closure and inclosing said valve member.
10. In an electro-magnetic organ valve, the combination with a valve casing having an opening in one side thereof, of a closure member for the opening, a valve seat formed on said closure member, a disc valve member, a valve guide carried by the closure including spring clip means for attaching said guide to said closure member and means for securing the closure member to the casing by the rotational movement of said closure member.
11. In an electro-magnetic organ valve, the combination with a valve casing having a threaded opening in one side thereof, of a threaded closure member for the opening, a valve seat formed on said closure member, a disc valve member, and an annular shaped valve guide carried by the closure member for limiting the vertical and lateral movement of said valve member relative to the valve seat.
12. In an electro-magnetic organ valve, the combination with a valve casing having a threaded opening in one side thereof, of a threaded closure member for the opening, a valve seat formed on said closure member, a disc valve member, and a valve guide carried by the closure member comprising an upwardly extending portion to limit the lateral movement of the valve member and an inwardly extending portion to limit the vertical movement of said valve member.
13. In an electro-magnetic organ valve, the combination with a valve casing having an opening in one side thereof, of a removable cover for the opening, including a valve seat, an electro-magnet mounted in the opposite wall of said casing, a disc valve element having a raised central portion, a valve guide mounted on said cover and having an inwardly projecting portion at the top thereof arranged to receive the raised central portion of the disc valve element within the valve guide when the removable cover is removed from the valve casing.
14. In an electro-magnetic organ valve, the combination with a valve casing having an opening in one side thereof, of a removable cover for the opening including a valve seat, a disc valve element, a valve guide mounted on the cover and inclosing the valve disc so as to positively retain said disc valve element within the valve guide when the cover is removed from the valve casing.
- In testimony whereof I affix my signature.
- HENRY E. BURTON.
